JOHN R. CARSON, OF MONTCLAIR, NEW JERSEY, ASSIGNOR TO AMERICAN TELEPHONE AND TELEGRAPH COMPANY, A CORPORATION OF NEW YORK.

SIGNALING SYSTEM.

Application filed July 7, 1920. Serial No. 394,509.

To all whom it may concern:

Be it known that I, JOHN R. CARSON, residing at Montclair, in the county of Essex and State of New Jersey, have invented certain Improvements in Signaling Systems, of which the following is a specification.

This invention relates to signaling systems and particularly to means associated with long signaling circuits to reduce the magnitude of interfering currents set up by extraneous causes to the lowest value consistent with the maintenance of a specified speed of transmission of signals.

Signaling waves transmitted over long signaling circuits such as submarine cable circuits are subjected not only to great distortion and attenuation by the circuit itself, but they are also liable to interference from sources usually extraneous to the cable itself which sets up within the circuit impulses of such magnitude as to "drown out" the received signaling wave. This is especially true where the interfering disturbance is set up within the cable at a point near the receiving end of the cable because the disturbance is not attenuated to the same degree as the signaling wave which travels the entire length of the cable.

The distortion and attenuation of signaling waves may be corrected by the use of distortion correction networks in combination with the thermionic amplifier, as shown in the copending application of Carson, Serial No. 240,631, filed June 18, 1918. One of the shortcomings of such an arrangement lies in the fact that both the signaling component and also the disturbing component of the received wave are amplified. If the disturbing component is stronger, as frequently it may be if the source of the interference is not remote from the receiving end, it will, when amplified, be so much greater in magnitude than the amplified signaling component as to render impractical the reading of the received signal.

It is the object of this invention to provide a suitable selective network adapted to prevent the passage therethrough of disturbing component and at the same time to effect the minimum interference to the passage of the signaling wave.

This invention will be understood from the following description when read in connection with the attached drawing, which

shows one form of embodiment of the invention.

In the figure 1 represents a submarine cable which is connected with one end of the winding 2 of the transformer 3, to the other end of which winding is connected the artificial line 5 which is adapted to balance the cable 1. Connected with the mid-point of the winding 2 is a conductor 6 by means of which the transmitting apparatus is connected to the cable to provide duplex operation. A second winding, 4, of the transformer 3 is connected with the input side of the interference suppression network A which is adapted to substantially eliminate the interference impulses, but at the same time to transmit therethrough the signaling wave without affecting, to any substantial degree, the signaling speed of the received signal wave. The output side of the network A is connected with the input side of the arrangement B, the function of which is to correct the signaling wave for the distortion created therein by the transmission over the cable circuit. The network illustrated at B is of the type shown in the pending Carson application, Serial No. 240,631, filed June 18, 1918, but it is to be understood that the invention is not limited to the use of this particular distortion correction network but that other networks adapted to perform the same function might be used. The output side of the arrangement B is connected to the circuit containing the receiving apparatus which may be of the well known type including for example, a relay and some form of recording instrument.

The network A comprises a plurality of unilateral devices 7, 10, 13, 16 and 19, the function of which is to prevent interaction between the subnetworks of which the circuit of network A is composed. Each of the subnetworks comprises a capacitance 8, 11, 14, 17 and 20, in combination respectively with a resistance 9, 12, 15, 18 and 21. The various subnetworks are separated from each other and also from the inductance 4 and the network B by means of the aforesaid unilateral devices. Although five subnetworks have been shown in the drawing, it is to be understood that the number is not so limited but that any number may be used depending upon the nature of the interference against which the receiving apparatus

is to be screened. If the interference is largely irregular a small number of subnetworks are preferable, while if high frequency sustained interference, a large number of subnetworks gives greater protection.

The determination of the proper values to be given to the various component elements of each subnetwork or stage of the interference network A may be determined approximately by the following rule. Let

R_o = The internal resistances of a tube 7, 10, etc.

R = The external resistances in the output circuit of the tube.

C = The capacity in parallel with R .

$$h = \frac{R + R_o}{R \times R_o \times C}$$

T = The approximate time required for the arrival curve to build up for a specified speed of signaling.

m = The number of subnetworks or stages in the circuit A.

It has been shown experimentally that if h is greater than $3m \div T$ the presence of a filter such as A will not materially affect the arrival curve and hence will not appreciably reduce the speed of propagation or alter the form of the wave of the received signals. Such an arrangement will, however, materially reduce the high frequency interference.

The arrangement represented by B comprises an amplifier 22 having its output side connected with the network comprising an inductance 23, a resistance 24, a capacitance 25, the latter being shunted by a resistance 26. Bridged across the circuit leading to the receiving apparatus is a resistance 27. The arrangement shown by B is adapted to produce not only the originally impressed wave, but also the first and second derivatives of the said wave, which when combined form a wave which is substantially the same as the wave form impressed upon the distant end of the submarine cable 1.

Since the terminal circuit is connected with the line circuit by means of the transformer 3, the potential set up in the secondary winding 4 of the said transformer is the first derivative of the current arriving over the line 1 and flowing through the primary winding 2 of the said transformer. The current arriving over the line 1 includes not only the attenuated signaling current but also the interference current that has been produced therein by extraneous sources. It will, accordingly, be seen that the potential applied to the grid of the vacuum tube 22 of the distortion correction device B is the first derivative of the received signaling current. The correcting network associated with the device B includes an inductance 23, a resistance 24 and a capacity 25 connected across the circuit, the capacity being

shunted by the resistance 26, which co-operates with the capacity for the purpose hereinafter pointed out and at the same time provides the proper circuit for the B battery of the amplifier. The plate electrode of the

amplifier is preferably connected somewhere between the ends of the inductance 23 to give an auto-transformer operation thereto, which facilitates voltage adjustments in the successive stages of the apparatus. The

total value of the inductance 23, as well as the relative value of parts on either side of the connection to the amplifier 7, must be proportioned with a view to the desired correcting effect as well as the desired step-up in voltage. Since the voltage impressed upon the grid of the vacuum tube 22 is the

first derivative of the received signaling current, the effect of the inductance 23 in the correcting network is to produce a second derivative of the received signaling current, which derivative has a steeper wave front than the said first derivative. The

voltage wave across the resistance 24 is the first derivative of the received signaling wave, and the wave resulting from the operation of the condenser 25 is the integral of the first derivative, that is to say, it is, in form, the arriving signaling current wave.

It will be apparent that by the proper adjustment of the various elements in the correcting network, the various component waves may be given proper values, so that their combined effect will be a wave having a fairly sharp rise with a fairly well sustained maximum value. In other words, it will approximate the form of the square topped current wave transmitted from the opposite end of the line, and accordingly, will be of the form most desirable for use

in recording apparatus. The condensers in series with the line and the bridged resistance 27 are designed to control the voltage impressed upon the succeeding amplifiers and have no bearing upon the reforming of the wave shape. The combination with an inductance in series with a resistance and a condenser, said condenser being shunted by a second resistance, the said combination being bridged across the line circuit, constitutes a very efficient form of restoring network, which, in effect, neutralizes the distortion and attenuation produced by the transmission of signals over long cable circuits.

Having in mind the foregoing description of the parts of the invention and the function that each performs, the invention will be clear from the following description of the mode of operation of the circuit. If the

voltage wave which has been attenuated and distorted by propagation over the cable 1, and has also been affected by interference due to extraneous causes, be impressed by the transformer 3 upon the input side of the

network A the said wave will be amplified by the vacuum tube 7 and will be impressed across the subnetwork comprising the capacitance 8 and the resistance 9. The effect of this network is to transmit with slight impedance the signaling frequencies and to tend to suppress the higher frequency impulses which represent the disturbance. The resultant wave is then impressed across the input side of the amplifier 10, with the output circuit of which are connected the capacitance 11 and the resistance 12. This latter network is adapted in similar manner to transmit readily the signaling frequencies and to tend to eliminate the higher frequency steep-sloped wave which represents the interference. It will be seen that by transmitting the impressed wave through a number of networks that the interference component will be substantially eliminated but that the signaling component as attenuated and distorted by propagation over the submarine cable will pass through the network A and be impressed upon the distortion correction arrangement B. The distorted wave will be amplified by the amplifier B and by means of the network shown associated therewith there will be derived and combined the received wave and its first and second derivatives. The restored signal wave, free from interference will then be impressed upon the receiving apparatus.

From the foregoing it will be seen that there has been provided in connection with the distortion correction arrangement shown in the said Carson application a network which is adapted to co-operate with the said distortion correction network to eliminate the effects of interference upon the signaling wave before any attempt is made to restore the distorted signaling wave to its transmitted form.

Although this invention has been disclosed as embodied in a certain form it is apparent that it is capable of embodiment in other and different forms within the scope of the appended claims.

What is claimed is:

50 1. In a signaling system the combination with a circuit characterized by great attenuation and distortion and exposed to interference from extraneous sources of a receiving circuit comprising an interference suppression network adapted to minimize the transmission therethrough of the interference component of the wave impressed upon the said receiving circuit, a distortion correction network adapted to restore substantially the signaling component of the impressed wave to its transmitted form and receiving apparatus adapted to have the said reform wave impressed thereon.

60 2. In a signaling system the combination with a submarine cable circuit having im-

pressed thereon a wave comprising a signaling component and an interference component of a receiving circuit comprising a filter adapted to prevent the passage therethrough of the interference component of the arrival wave, a distortion correction device adapted to restore the signaling component of the arrival wave substantially to its transmitted wave shape and receiving apparatus.

3. In a signaling system the combination with a submarine cable circuit of a receiving circuit comprising an interference elimination network and a distortion correction network, the said interference elimination network having a plurality of subnetworks each comprising a unilateral device having internal resistance R_o , a condenser of capacitance C and resistance R bridged in parallel across the output side of the said device whereby interference may be prevented without diminishing the signaling speed provided the ratio $\frac{R_o + R}{CR_o}$ is greater than the ratio represented by three times the number of subnetworks divided by the period of time required for the arrival wave to reach the amplitude for the required signaling speed.

4. In a signaling system the combination with a circuit characterized by great distortion and attenuation and having impulses induced therein by external sources of a receiving circuit comprising an interference eliminating arrangement having a thermionic amplifier of internal resistance R_o and a condenser of capacitance C and a resistance R bridged in parallel across the output side of the said amplifier whereby the interfering impulses may be eliminated provided the ratio of $\frac{R_o + R}{CR_o}$ is greater than the

ratio represented by three times the number of stages of amplification divided by the period required for the arrival wave to reach the amplitude required for signaling speed.

5. In a signaling system, the combination with a line circuit of a plurality of low-pass filters, a plurality of unilateral devices inserted between the adjacent filters, a distortion correction network and a unilateral device inserted between the said correction network and the last low-pass filter, the correction network comprising an inductance in series with a resistance, and a condenser connected across the output side of the said unilateral device.

6. In a signaling system, the combination with a line circuit of a plurality of low-pass filters, a plurality of unilateral devices inserted between adjacent filters, a distortion correction network, and an amplifier connected between the said correction network and the last low-pass filter, the said correc-

tion net-work including an inductance in series with a resistance, and a condenser bridged across the output side of the said amplifier, the said condenser being paralleled by a second resistance.

7. The method of improving the transmission of signaling currents over a circuit adapted to distort the shape of the signals and also adapted to have set up therein interfering currents from external sources which consists in receiving the signaling and the interfering currents, producing the first derivative of the received currents, passing those currents having a frequency below a predetermined limit and suppressing those above, amplifying the currents passed, producing the integral and the second derivative of the amplified currents, combining those with the said first derivative to reform the signal, and producing an indication of the said signal.

8. The method of improving the transmission of signaling currents over a circuit adapted to distort the shape of the signals and also adapted to have set up therein interfering currents from external sources which consists in receiving the signaling and the interfering currents, producing the first

derivative of the received currents, passing those currents having a frequency below a predetermined limit and suppressing those above, amplifying the currents passed, producing the integral and the second derivative of the amplified currents, combining those with the said first derivative to reform the signal, and producing an indication of the said signal.

9. The method of improving the transmission of signaling currents over a circuit adapted to distort the shape of the signals and also adapted to have set up therein interfering currents from external sources which consists in receiving a plurality of frequencies representing a signaling impulse and an interfering wave, suppressing the frequencies of the interfering wave and passing the frequencies of the signal, amplifying the signal frequencies, reforming the shape of the signal impulse, and producing an indication of the signal as reformed.

In testimony whereof, I have signed my name to this specification this 2 day of July, 1920.

JOHN R. CARSON.
